PERISCOPE-TYPE REARVIEW MIRROR

Lynn Harold Hodge, 841 McNichols W.,
Highland Park, Mich. 48203

Filed Apr. 6, 1970, Ser. No. 22,263

Term of patent 3½ years

Int. Cl. D12—14

U.S. Cl. D14—6 M

FIG. 1 is a 3/4 rear view of a periscope-type rearview mirror.

FIG. 2 is a 3/4 rear view from below.

FIG. 3 is a 3/4 front view from above.

FIG. 4 is a side view.

The automobile roof shown in broken lines is included for illustrative purposes only.

I claim:

The ornamental design for a periscope-type rearview mirror, substantially as shown and described.
